UNITED STATES PATENT OFFICE.

CHARLES W. HINMAN AND WALTER HIBBARD HINMAN, OF WINCHESTER, MASSACHUSETTS.

GAS-METER.

1,250,176.

Specification of Letters Patent. Patented Dec. 18, 1917.

Application filed May 14, 1917. Serial No. 168,500.

To all whom it may concern:

Be it known that we, CHARLES W. HINMAN and WALTER HIBBARD HINMAN, both citizens of the United States, residing at 5 Winchester, in the county of Middlesex and State of Massachusetts, have invented certain new and useful Improvements in Gas-Meters; and we do hereby declare the following to be a full, clear, and exact description 10 of the invention, such as will enable others skilled in the art to which it appertains to make and use the same.

The present invention relates to wet gas meters of the class commonly known as station meters. The object of the present invention is to improve the construction of the type of meter disclosed in Patent No. 1,221,179, granted to us April 3, 1917, by rendering the same more efficient in operation, increasing 15 the strength and rigidity of the same, and reducing the cost of manufacture. With these and other objects in view, as will hereinafter appear, the present invention consists in the devices and arrangements hereinafter described and more particularly defined 20 in the claims.

In the accompanying drawings which illustrate what is now believed to be the preferred form of the present invention, Figure 30 1 is a longitudinal vertical section of our improved meter; Fig. 2 is a sectional end view on the line 2—2, Fig. 1; Fig. 3 is an outlet end view of the drum on a somewhat smaller scale; and Fig 4 is a perspective view 35 of one of the division walls and the end walls connected therewith.

The improved gas meter illustrated in the drawings comprises the usual stationary casing 1, having at one end the axial gas 40 inlet pipe or dry well 2 and the outlet pipe 3 near the periphery. It is provided in its interior with the bearings 4 for the shaft 5 of the revolving measuring drum, the greater portion of which is always submerged beneath 45 the water which fills the casing to a level slightly below the upturned end of the inlet pipe 2 as indicated in Fig. 1. The ends of the casing 1 differ, however, from our prior patent above referred to in that they 50 are frusto-conical as shown at 6, giving to the casing a generally octagonal shape in longitudinal cross-section. A convenient way of forming the casing is that shown in Fig. 1, where the body or cylindrical portion 55 is formed with a flange at each end, to

which flanges are riveted the flanges on the frusto-conical end members 6.

The revolving measuring drum which is located within the casing is slightly smaller but of the same general shape as the casing, 60 being of general octagonal form in longitudinal cross-section, as shown in Fig. 1, instead of being substantially cylindrical as in our prior patent referred to. This drum comprises a cylindrical shell 7, provided on 65 its interior with division walls to form the measuring compartments and having end walls closing the ends of the drum except for the inlet and outlet ports for the gas. The outer shell, the interior division walls, 70 and the end walls are rigidly supported on the shaft 5 by means of a frame-work or bracing, as will hereinafter appear.

The division walls, as shown in Fig. 4, are composed of a plurality of sections, the 75 alternate sections such as 8, 9, 10, 11, and 12, being angularly disposed with relation to each other, but with the middle section 10 co-planar with the axis and the other sections 8, 9, 11, and 12 parallel with the 80 axis. Adjacent and between these sections are other sections 13, 14, 15, 16, 17, 18, 19, and 20 all oblique to the axis of the drum and angularly arranged with relation to each other. Extending along the inner edge 85 of the sections 8, 9, 10, 11, and 12 is a radial portion 21 which is co-planar with section 10 and with the axis of the drum. The inner edge of this radial portion 21 never rises above the level of the water in the casing. Its highest position is indicated in 90 Fig. 1 as slightly below the water level.

The space between the inner edges of adjacent sections 21 constitutes the port 95 through which the water flows into and out of the measuring chamber as such chamber in the rotation of the drum is submerged below the water level and then lifted above the same.

The end walls of the measuring chamber 100 are similar to those of our prior patent except that instead of being substantially perpendicular to the axis of the drum, they are, save for a small perpendicular portion adjacent the axis, of frusto-conical shape. Thus 105 in Fig. 4 the inlet end wall 24 is a portion of a surface of frusto-conical shape except the portion 25 nearest the axis. Similarly the outlet end wall 27 is also a portion of a frusto-conical surface except for the small 110

portion 28 nearer the axis. Both inlet and outlet end walls are connected to the division walls by sections 31 and 32 respectively, which in Fig. 4 are shown as having 5 plane surfaces instead of being curved as in our prior patent.

The gas inlet ports 33 between the end walls of adjacent measuring chambers are of greater width at their inner or axial ends 10 than at their outer or peripheral ends, differing in this respect from the inlet ports of our prior patent, which are of substantially uniform width throughout their length. The gas outlet ports 34 are also of greater 15 width in our present meter at their axial ends than at their peripheral ends.

The drum with its division and end walls is supported upon a frame-work carried by a number of hubs secured upon the shaft 5. 20 In the construction shown in Fig. 1, five hubs are employed, two end hubs 35, 35, adjacent the bearings for the shaft, a middle hub 36 substantially midway between the end hubs, and two intermediate hubs 37, 37, one between the middle hub and each end hub. The end and intermediate hubs 35 and 37 are of a shape resembling generally a Greek cross and comprise a cylindrical portion 40 upon the shaft, the spokes 41 radiating therefrom, and the cross-shaped rim 42 carried by the spokes, as shown in Fig. 2. Preferably the rim of the hub is slightly 25 unsymmetrically arranged, as shown in Fig. 2, for convenience in attaching the frame-work and braces as hereinafter described. The middle hub is a plain cylindrical hub having four short arms extending therefrom as shown in Fig. 2, to which arms certain of the braces are riveted.

40 Each of the hubs carries riveted thereto four angle iron arms or supports extending from the hub to the outer shell of the drum. The arms or supports 44, carried by the end hubs 35 are arranged at a slight angle to a 45 radius as shown in Fig. 2. Their outer ends are bent toward the middle of the drum as shown in Fig. 1, the arms at the outlet end having a sharper bend at a point nearer the hub than the arms at the inlet end. The arms 46 from the intermediate 50 hubs 37 are also at a slight angle to the radius, but instead of being bent at some point between their inner and outer ends are obliquely attached to the hubs as shown at 55 Fig. 1. Both arms 44 and 46 are further supported intermediate their ends by the angle iron braces 48 carried by the hubs 35 and 37 as shown in Fig. 2. The arms 50 from the middle hub 36 are radially disposed as shown in Fig. 2 and are slightly oblique to a plane perpendicular to the axis 60 as shown in Fig. 1. These arms 50 are further supported by the diagonal braces 52 extending from the tangential faces of the 65 intermediate hubs 37, 37, to the arms 50

about midway between the inner and outer ends thereof.

The outer ends of all five sets of arms are secured to the shell of the drum and to rings or bands 54 extending around the outer surface thereof. Different portions or sections of the division walls are attached directly to these different arms. For example, as shown in Fig. 1, the middle section 10 and inner radial portion 21 are attached to the middle arm 50 and diagonal braces 52. The portion 9 is attached to the arm 46 nearer the inlet, while the corresponding portion 11 is attached to the arm 46 nearer the outlet end of the drum.

From the foregoing description it will be evident to those skilled in the art that by forming the ends of the drum of frusto-conical shape the effective length of the gas-measuring chamber will be reduced without 70 reducing the length of the port through which the water passes into and out of the chamber as the drum rotates. As a result 75 the ratio of water-port to capacity of the gas-chamber is increased and the filling and 80 emptying of said gas-measuring chamber is accomplished in a shorter time and with the expenditure of less energy. The formation 85 of the inlet and outlet gas ports with a greater width at their axial ends than at 90 their peripheral ends also facilitates the filling and emptying of the measuring chamber. Furthermore, owing to the frusto-conical shape of the ends of the drum the 95 surface area of the drum in contact with the 100 water in the casing is reduced, diminishing correspondingly the skin friction or resistance offered by the water to the turning of 105 the drum. As a result of these several features of construction the speed of rotation 110 of the measuring drum is very substantially increased and to such an extent that a much greater volume of gas can be passed through and measured in a meter constructed in accordance with the present invention than in 115 one having the same axial length and diameter but having square ends instead of frusto-conical, and this notwithstanding the greater capacity per revolution of the meter with square ends.

Furthermore, a meter constructed in accordance with the present invention is of greater strength and rigidity, a feature of great importance with meters of this class which may have a diameter of sixteen feet 120 or more.

Another advantage obtained by the present construction is the saving in the cost of material, both for the drum and for the casing, as will be readily apparent to those 125 familiar with this class of apparatus.

While in the preferred embodiment of the present invention illustrated in the drawings, our improved meter drum is shown with both inlet and outlet ends of frusto-

conical shape, it is to be understood that the present invention is not necessarily limited to such a construction except where so specifically stated in the claims, as some 5 of the advantages of our present invention will be secured, although perhaps to a lesser degree, by having one end only of frusto-conical form, or by adopting a shape other than that of the surface of the frustum of 10 a cone, one of the principal features of our invention being the formation of a measuring chamber of less effective axial length than the water-port in order to facilitate the filling and emptying of said chamber as 15 the measuring drum is rotated.

Having thus described the present invention, what is claimed is:—

1. In a gas meter, the combination with a stationary casing, of a drum mounted to 20 revolve therein comprising an outer shell having internal division walls to form measuring chambers, said chambers being of greater axial length nearer the axis than adjacent the outer shell, and means for rotatably supporting the drum in the casing.

2. In a gas meter, the combination with a stationary casing, of a drum mounted to revolve therein comprising an outer shell having internal division walls to form measuring 30 chambers and end walls for the same, the outer portions of the end walls of each chamber at one end of the drum being located nearer the opposite end of the drum than are the inner portions of such end 35 walls, and means for rotatably supporting the drum in the casing.

3. In a gas meter, the combination with a stationary casing, of a drum mounted to revolve therein comprising a cylindrical 40 shell provided with internal division walls forming measuring chambers and with end walls for the same, the end walls of each chamber converging outwardly from the axis of the drum, and means for rotatably 45 supporting the drum in the casing.

4. In a gas meter, the combination with a stationary casing, of a drum mounted to revolve therein comprising an outer shell having a body portion and convex ends, and 50 provided with internal division walls form-

ing measuring chambers, and means for rotatably supporting the drum in the casing.

5. In a gas meter, the combination with a stationary casing comprising a substantially cylindrical body portion and frusto-conical ends, of a drum mounted to revolve therein, said drum comprising an outer shell having a substantially cylindrical body portion, and frusto-conical ends, and provided with internal division walls forming measuring 55 chambers, and means for rotatably mounting the drum in the casing.

6. In a gas meter, the combination with a stationary casing, of a drum comprising an outer shell having internal division walls 60 forming measuring chambers and end walls for the same, the end walls of adjacent chambers being spaced apart to form ports, the ports at one end of the drum being of greater width at their inner or axial ends 65 than at their outer ends, and means for rotatably supporting the drum in the casing.

7. In a gas meter, the combination with a stationary casing, of a drum mounted to revolve therein comprising an outer shell 70 provided with internal division walls to form measuring chambers and with end walls for the same, said chambers being of greater axial length nearer the axis than adjacent the outer shell, and the end walls 75 of adjacent chambers being spaced apart to form ports, the ports at one end of the drum being of greater width at their inner or axial ends than at their outer ends, and means for rotatably supporting the drum 80 in the casing.

8. In a gas meter, the combination with a stationary casing of a drum mounted to revolve therein comprising a cylindrical 85 shell provided with internal division walls forming measuring chambers and with end walls for the same, the axial portion of the end walls of the chambers at one end of the drum projecting axially beyond the peripheral portions of said end walls, and means 90 for rotatably supporting the drum in the casing.

CHARLES W. HINMAN.
WALTER HIBBARD HINMAN.
